UNITED STATES PATENT OFFICE.

JOSEPH EIFEL, OF CHICAGO, ILLINOIS.

WRENCH.

1,244,966.

Specification of Letters Patent. Patented Oct. 30, 1917.

Original application filed June 26, 1912, Serial No. 706,079. Divided and this application filed April 8, 1916. Serial No. 89,958.

To all whom it may concern:

Be it known that I, JOSEPH EIFEL, a citizen of the United States, and a resident of Chicago, in the State of Illinois, have invented certain new and useful Improvements 5 in Wrenches, of which the following is a specification.

My present invention relates to wrenches in general and more particularly to wrenches 10 having variable jaw openings, and has special reference to the provision of an improved wrench embodying the most valuable features of wrenches of a number of different types known to me, and avoiding the defects thereof.

The principal objects of my present invention are the provision of a wrench having jaws one of which may be rapidly moved 20 relatively to the other, a wrench thus characterized which will not tend to work open in handling, thus requiring repeated settings or adjustments during a single operation, one which will have small crushing effect tending to abrade, flatten or otherwise disfigure 25 articles upon which it is used; the provision of an improved plier form wrench adapted for wide separation of the jaws without concurrent wide opening of the handles and one wherein relatively slight manipulation is required either in moving the article acted 30 upon or in obtaining a fresh hold thereupon; the provision of a wrench wherein the parallelism of the jaws may be readily maintained irrespective of the size of the object operated 35 upon; the provision of a wrench wherein the number of contact points of the jaws thereof with the article operated upon may be increased and generally to provide an improved and more efficient type of wrench 40 than is at this time available, together with such further and additional objects as may hereinafter appear.

Certain embodiments of devices involving, in part, my present improvements, are shown 45 in my co-pending application for Letters Patent, Serial No. 706,079, filed June 26, 1912, of which the present application is a division.

In gaining the objects above mentioned, 50 as well as certain further benefits and advantages to be below pointed out, I have provided the constructions illustrated in the accompanying drawings, wherein—

Figure 1 is a plan view illustrative of my 55 invention embodied in a wrench wherein, as

shown, adjustable pliers having jaws which are variable not only in their degree of separation, but also in the degree of angularity of their operative relation to each other, are provided.

Fig. 2 is an elevational view of the wrench of Fig. 1, partly in section taken on the line 2—2 of Fig. 1;

Figs. 3 and 4 are elevational views of modified forms of jaws applicable to the 65 wrenches of the present type.

Referring now more particularly to the device of Figs. 1 and 2 it will be observed that I have here illustrated a wrench embodying my invention in the form of a pair of pliers, 70 wherein the gripping faces of the jaws are not only variable in their parallelism relatively to each other, but may be arranged in any required degree of angularity between parallelism and a right angle relatively to 75 the longitudinal axis of the operating handles, and by suitable modification of their position, or the use of the jaws illustrated in Figs. 3 and 4 may readily be adapted for one or more of the following purposes, an adjustable wrench, adjustable pliers, parallel pliers, adjustable pipe tongs, wire cutter, etc. In this embodiment of my invention it will be seen upon examination of the drawings, that in the arrangement of jaws, instead of employing the direct engagement 80 between the segment and rack disclosed in the original application, I here interpose a gear wheel whereby certain angularities of adjustment are made possible, all as now to 85 be described.

It will be seen that in my present construction I employ a shank 10 provided at one end with a handle 11 and at the opposite end with a jaw 12, pivoted thereto at 12^a 95 and slotted as indicated at 13 for the reception of the shank 14 which is provided with a jaw 15 and engages by means of a pin 19 a slot 23 in said jaw 12, a roller bearing 24 being interposed between the jaw 12 and the shank 14. On the pivot pin 12^a is rotatably mounted a pinion having a toothed periphery 22 engaging a rack 16 formed on the shank 14, and likewise engaging a segmental rack 22^a formed on the operating 100 lever 17, which has pivotal engagement with the shank 10 as indicated at 18, and is slideable relatively thereto by means of the slot 20 in which said pin 18 is movably carried.

For normally preventing movement of 110

the jaw 12 relatively to the shank 10 I provide on the extensions 75 of said jaw 12 toothed segments 76 which engage complementary toothed segments 77 on a lever 78 movable upwardly in the hollow handle 10, but normally held in position shown by means of a spring 79, such lever 78 being bifurcated and the bifurcated portions thereof being carried on the pin 18. For holding the handles 11 and 17 in the relative position shown I employ a pawl 37 pivoted at 38 in the handle 17 and normally engaging the ratchet 39, such pawl being provided with an extension 37^a against which the spring 40 acts in order to maintain the engagement with the ratchet, a sliding block 38 being employed to release the engagement when desired.

In the operation of the device above described, it will be observed that moving the slide 38^a disengages the pawl 37 from the ratchet 39 and allows the handles 17 and 11 to be separated. Upon lowering the handle 17 obliquely to the left, and pressing upwardly upon the lever 78, thereby disengaging the handles 17 and 10 from the pinion 22, and the jaw 12 respectively, the jaws 12 and 15 may be varied in the amount of their separation, whether they be parallel as shown or angularly disposed, and the faces 80 and 81 may be formed with any desired degree of angularity from the parallelism shown up to a right angle. Upon releasing pressure upon the lever 78 the toothed portion 77 thereof will again engage with the toothed portion 76 of the jaw 12 fixing it in position relatively to said lever 10, and upon the lever 17 being moved to the position shown, the toothed segment 22^a thereof will engage the pinion 22 in turn acting upon the rack 16 and moving the jaw 15 toward the jaw 12.

From the foregoing description of the construction and operation of the present embodiment of my invention, it will be observed that the type here disclosed is provided with means whereby the jaws may be instantly opened and closed to a limited extent for shifting relatively to the work, thereby making it feasible to utilize notches such as 50-51 for the purpose of engaging the corners, as well as flat faces of nuts, giving a much firmer hold thereupon. It will thus be observed that by the use of the embodiments of my invention illustrated I am able where it is desirable to engage a nut on parallel faces, on opposed corners, or on a corner opposed to a face, with more holds and thus with firmer engagement than it is possible with any form of a wrench known to me. Since the pressure applied upon closing the wrench may be readily varied, it is obvious that the pressure applied to any nut, pipe or other object worked upon may be gaged to suit conditions with the greatest

of facility. Other advantages of my present invention will be apparent to those who are skilled in the art to which it pertains.

Having thus described my invention and illustrated its use, what I claim as new and desire to secure by Letters Patent is:

1. A device of the character described comprising, in combination, a pair of co-operating jaws and pivoted operating levers therefor, and connections, disengageable by manual means, between each of said jaws and its co-operating lever.

2. A device of the character described comprising, in combination, a pair of co-operating jaws, operating levers therefor having means for engagement whereby they are movable pivotally and lineally relatively to each other, one of said jaws being movable relatively to its lever and having means for toothed engagement therewith whereby the extent of the jaw opening may be varied.

3. A device of the character described comprising, in combination, a pair of co-operating jaws, operating levers therefor having means for engagement whereby they are movable pivotally and lineally relatively to each other, one of said jaws being movable relatively to its lever and having means for toothed engagement therewith whereby the extent of the jaw opening may be varied, and means for normally preventing relative lineal movement of the levers.

4. A device of the character described comprising, in combination, a pair of co-operating jaws, pivoted operating levers therefor, one of said jaws being operatively movable relatively to its lever and both the lever and the jaw being provided with toothed portions, an intermediate toothed member engaging said toothed portions whereby the relative position of the jaws may be varied, and means for normally holding the jaws in predetermined operative relation to each other.

5. A device of the character described comprising, in combination, a pair of co-operating jaws, operating levers therefor having means for engagement whereby they are movable pivotally and lineally relatively to each other, one of said jaws being movable relatively to its lever and both the lever and the jaw being provided with toothed portions, an intermediate toothed member engaging said toothed portions whereby the relative position of the jaws may be varied, and means for normally holding the jaws in predetermined operative relation to each other.

6. A device of the character described comprising, in combination, a pair of co-operating jaws, operating levers therefor having means for engagement whereby they are movable pivotally and lineally relatively to each other, one of said jaws being movable relatively to its lever and both

the lever and the jaw being provided with toothed portions, an intermediate toothed member engaging said toothed portions whereby the relative position of the jaws 5 may be varied, and means for normally holding the jaws in predetermined operative relation to each other including a toothed portion on one of said jaws, and a third lever provided with a toothed portion 10 engaging said last-mentioned toothed portion.

7. A device of the character described comprising, in combination, a pair of co-operating jaws, operating levers therefor 15 having means for engagement whereby they are movable pivotally and lineally relatively to each other, one of said jaws being movable relatively to its lever and both the lever and the jaw being provided with 20 toothed portions, an intermediate toothed member engaging said toothed portions whereby the relative position of the jaws may be varied, and means for normally holding the jaws in predetermined operative 25 relation to each other including a toothed portion on one of said jaws and a third lever provided with a toothed portion engaging said last mentioned toothed portion and a spring for maintaining such engagement.

8. A device of the character described, comprising in combination, a pair of co-operating jaws and pivoted operating levers therefor, both of said jaws being movable 35 relatively to their respective levers, one of said levers and its jaw being both provided with toothed portions and an intermediate toothed member engaging said toothed portions.

40 9. A device of the character described comprising, in combination, a pair of co-operating jaws, pivoted operating levers therefor, one of said jaws being operatively movable relatively to its lever and both 45 the lever and the jaw being provided with means for engagement, an intermediate member engaging said means whereby the relative position of the jaws may be varied, and means for normally holding the jaws 50 in predetermined operative relation to each other.

10. A device of the character described comprising, in combination, a pair of co-operating jaws, operating levers therefor 55 having means for engagement whereby they are movable pivotally and lineally relatively to each other, one of said jaws being movable relatively to its lever and both the lever and the jaw being provided with means 60 for engagement, an intermediate member engaging said means whereby the relative position of the jaws may be varied, and means for normally holding the jaws in predetermined operative relation to each other.

65 11. A device of the character described

comprising, in combination, a pair of co-operating jaws and pivoted operating levers therefor, and connections, disengageable by manual means, between each of said jaws and its co-operating lever, whereby the 70 width of opening of said jaws may be varied without change in angular relationship of the levers with respect to each other by varying the connection of either lever with respect to its co-operating jaw. 75

12. A device of the character described comprising, in combination, a pair of co-operating jaws, toothed portions operatively connected with each of said jaws, an operating lever pivotally attached to one 80 of said jaws, and a second operating lever pivotally attached to said first lever, each of said levers having a toothed portion operatively connected therewith adapted to engage one of said first-mentioned toothed 85 portions.

13. A device of the character described comprising in combination, a pair of co-operating jaws, a pair of operating levers for said jaws and means, disengageable by manual means, for varying the angular relation 90 between each lever and its co-operating jaw.

14. A device of the character described comprising in combination, a pair of co-operating jaws and pivoted operating levers 95 therefor, both of said jaws having connections, disengageable by manual means, with their respective levers, including a variable gear connection between one of said levers and its jaw whereby the position of 100 said jaw relatively to its lever may be varied.

15. A device of the character described, comprising in combination a pair of co-operating jaws, a segmental toothed portion integrally connected to one of said jaws, and 105 an operating lever having a toothed portion operatively connected thereto adapted to engage said segmental toothed portions in a plurality of relative positions whereby the angular relation between said lever and said 110 jaw may be varied.

16. A device of the character described, comprising in combination, a pair of co-operating jaws adapted to slide transversely relatively to each other, a pair of operating 115 levers, connections between said levers and said jaws whereby movement of said levers toward each other moves said jaws toward each other; and means, disengageable by manual means, for varying the angular relation between each lever and its co-operating jaw.

17. A device of the character described comprising, in combination, a pair of co-operating jaws slidable relatively to each other 120 transversely of the device, pivoted operating levers therefor, and connections, disengageable by manual means, between each of said jaws and its co-operating lever.

18. A device of the character described, 130

comprising in combination, a pair of coöperating jaws slideable relatively to each other transversely of the device and pivoted operating levers therefor, each of said jaws being movable relatively to its lever and having means for manually releasable engagement therewith whereby the extent of the jaw opening may be varied.

In testimony whereof I have hereunto signed my name in the presence of the two 10 subscribing witnesses.

JOSEPH EIFEL.
